INVENTOR

UNITED STATES PATENT OFFICE.

JOHN REEK, OF CAMDEN, MICHIGAN, ASSIGNOR TO THE ALAMO MANUFACTURING COMPANY, OF HILLSDALE, MICHIGAN.

GAS-ENGINE IGNITION-DYNAMO.

SPECIFICATION forming part of Letters Patent No. 778,146, dated December 20, 1904.

Application filed March 16, 1903. Serial No. 147,881.

To all whom it may concern:

Be it known that I, JOHN REEK, a citizen of the United States, residing at Camden, county of Hillsdale, State of Michigan, have invented 5 a certain new and useful Improvement in Gas-Engine Ignition-Dynamos; and I declare the following to be a full, clear, and exact description of the invention, such as will enable others skilled in the art to which it pertains to 10 make and use the same, reference being had to the accompanying drawings, which form a part of this specification.

This invention relates to gas-engine ignition-dynamos; and the object of the invention 15 is to so construct the mounting of a dynamo and to so connect it with the source of power by which it is actuated that it shall produce a substantially constant voltage without employing special governing mechanism.

20 In the drawings, Figure 1 shows the dynamo in perspective with the driving-wheel of the armature in frictional contact with the balance-wheel of an engine. Fig. 2 is a reversed or bottom plan of the dynamo-base. Fig. 3 25 is a sectional detail of a part of the base.

The dynamo A may be of any selected form best adapted to the purpose of producing the requisite number of watts for the desired spark. It receives its motive power through 30 the small driving-wheel B, that is fixed to the armature-shaft and is arranged to be driven by frictional contact with the balance-wheel C of the internal-combustion engine.

The dynamo is mounted pivotally on a base 35 and is arranged to swing on a frame E to bring its driving-wheel B into a frictional contact of any desired tension with the balance-wheel C.

The base D is made separate from the main frame of the dynamo, and in the base there is 40 a ball-race *e* of comparatively large diameter, and on the frame E of the dynamo is a corresponding ball-race *f*, arranged to register with the ball-race in the base D. In the assembled machine the space between the two races contains a number of bearing-balls *a*.

45 *g* is an aperture through a part of the base D, through which aperture the balls may be inserted into the races *e* and *f*, thus binding

the frame E to the base D and forming a swivel-joint. 50

A spring *b* is made fast to the dynamo-frame and is provided with an adjustable tension-screw *c*, which engages through a fixed holding-point in the base D. By means of the screw the tension of the spring *b* can be ad- 55 justed as may be desired.

The dynamo is mounted with respect to the engine so that the driving-wheel B is in frictional contact with the balance-wheel C of the engine and is drawn against the balance-wheel 60 C by the spring *b* with sufficient force to cause the armature B to rotate at the proper speed to generate the desired watts. In determining this the relative size of the wheel C and the wheel B are taken into consideration. The 65 wheel B is made in the first instance of a size proper to produce the rotation necessary for the generation of a current of the desired number of watts when the wheel C is running at a slow rate of speed. Such a speed will be given 70 to the balance-wheel when the engine is started by manual rotation of the parts. If now when the parts are in proper adjustment the speed of the wheel C increases, tending to increase the speed of the wheel B, and consequently 75 tending to undesirably increase the output of the dynamo, the peripheral velocity of the wheel B will not increase with that of the wheel C; but as I have found from experimental observation it causes the small wheel to 80 swing a short distance away from the wheel C, thereby preventing any increase of the speed of rotation of the small wheel and causes the output of the dynamo to remain very nearly 85 constant, and the amount of the output of the dynamo in watts can be easily regulated by adjusting the tension of the spring *b*. With the roller-bearings the rollers contact their ways in points or lines which are very small, and therefore allow a slight resilient motion 90 under the impulse of the fly-wheel.

What I claim is—

1. In a gas-engine, the combination of a rotating fly-wheel, a dynamo, an armature in said dynamo, a friction-wheel secured at one 95 end of said armature, said dynamo being piv-

oted so as to turn in a plane at an angle with the plane of rotation of said fly-wheel to bring said friction-wheel against and away from the periphery of the fly-wheel, and a spring 5 acting to turn the dynamo to bring the friction-wheel into contact with the periphery of the fly-wheel, the tension of said spring being such that the engagement between the fly-wheel and the friction-wheel shall be sufficient 10 so that the two shall move together at slow speed and shall be broken automatically at a predetermined speed limit of rotation of the armature.

2. In combination with the balance-wheel 15 of an explosive-engine, a dynamo mounted upon a roller-bearing so as to turn about an axis at right angles to the axis of the armature, a friction-wheel upon the armature-shaft eccentric to the axis about which the dynamo 20 is adapted to turn, said dynamo being so located with reference to said balance-wheel that its turning shall press said friction-wheel against the outside of said balance-wheel, and a spring adjusted to turn the dynamo to 25 hold the friction-wheel against the periphery of the balance-wheel with a force sufficient to produce the necessary friction at slow speed and that shall yield at a speed of rotation adapted to furnish predetermined maximum 30 current.

3. In combination with the balance-wheel of an explosive-engine, a dynamo-base, an internal opening in said base, the bounding-

wall of said opening being provided with a ball-race, a dynamo having a frame provided 35 with a ball-race adapted to register with the ball-race in the base, balls in said races, a friction-wheel on the armature of said dynamo at one side of the axis of rotation of said dynamo, means for holding the friction-wheel in yielding engagement with the balance-wheel, and means for regulating the tension of the yielding engagement.

4. In combination with the balance-wheel of an explosive-engine, a dynamo-base having 45 an internal opening, the bounding-wall of said opening being provided with a ball-race, a dynamo having a frame provided with a ball-race adapted to register with the ball-race in the base, an opening through the base 50 for the passage of balls, balls in said races, a friction-wheel on the armature of said dynamo at one side of the axis of rotation of said dynamo, a spring engaging at one end with the dynamo-base and at the other end with the 55 frame at a point eccentric to said frame, and means for adjusting the tension of said spring whereby the friction-wheel shall be held in an adjustable yielding engagement with the balance-wheel.

In testimony whereof I sign this specification in the presence of two witnesses.

JOHN REEK.
